POCKET KNIFE

Thomas R. Arden, Danbury, Conn., assignor to
Bard-Parker Company, Inc., Danbury, Conn.,
a corporation of New York

Application March 7, 1951, Serial No. 14,410

Term of patent 14 years

(Cl. D22—3)

To all whom it may concern:

Be it known that I, Thomas R. Arden, a citizen of the United States, residing at Danbury, county of Fairfield, State of Connecticut, have invented a new, original, and ornamental Design for Pocket Knife, of which the following is a specification, reference being had to the accompanying drawing, forming a part thereof.

Figure 1 is a side elevational view of a pocket knife, showing my new design;

Figure 2 is a top plan view thereof;

Figure 3 is a side elevational view thereof, showing the side opposite that shown in Figure 1;

Figure 4 is a bottom plan view thereof;

Figure 5 is a side elevational view of the pocket knife shown in Figure 1, with the blade in open position;

Figure 6 is a top plan view thereof, with the knife open as shown in Figure 5;

Figure 7 is a side elevational view thereof, showing the side opposite that shown in Figure 5;

Figure 8 is a bottom plan view thereof, with the knife open as shown in Figure 5; and

Figure 9 is a cross-sectional view thereof, taken on line 9—9 in Figure 1.

I claim:

The ornamental design for a pocket knife, as shown.

THOMAS R. ARDEN.
